United States Patent

[19]

Garza**Patent Number: Des. 422,057****Date of Patent: ** Mar. 28, 2000**

[54] **HOSE END TRIGGER HIGH PRESSURE SPRAY NOZZLE**

[75] Inventor: **Richard G. Garza**, Norwalk, Calif.

[73] Assignee: **Arcadia Industries, Inc.**, San Diego, Calif.

[**] Term: **14 Years**

[21] Appl. No.: **29/106,920**

[22] Filed: **Jun. 23, 1999**

[51] LOC (6) Cl. **23-01**

[52] U.S. Cl. **D23/226**

[58] Field of Search **D23/213, 223, D23/226, 229; 239/525-528**

[57] **CLAIM**

The ornamental design for a hose end trigger high pressure spray nozzle, as shown and described.

DESCRIPTION

FIG. 1 is a side elevational view of a hose end trigger high pressure spray nozzle embodying my new design, it being understood that the opposite end is a mirror image thereof;

FIG. 2 is a front elevational view thereof;

FIG. 3 is a rear elevational view thereof;

FIG. 4 is a top plan view thereof; and

FIG. 5 is a bottom plan view thereof.
